FRONT PANEL FOR VENDING MACHINE FOR POSTAL SUPPLIES

William A. Gran, Independence, Mo., assignor to The
Vendo Company, Kansas City, Mo., a corporation of
Missouri

Filed May 11, 1966, Ser. No. 2,260

Term of patent 14 years

(Cl. D52—3)

FIG. 1 is a front elevational view of the front panel for a vending machine for postal supplies; and

FIG. 2 is a sectional view taken on line 2—2 of FIG. 1. The dominant features of my design reside in the portions shown in full lines.

I claim:

The ornamental design for a front panel for a vending machine for postal supplies, as shown and described.
